UNITED STATES PATENT OFFICE

162,285

TRAY

John Cauffiel, Toledo, Ohio

Application February 1, 1950, Serial No. 7,623

Term of patent 14 years

(Cl. D44—10)

To all whom it may concern:

Be it known that I, John Cauffiel, a citizen of the United States, residing at Toledo, State of Ohio, have invented a new, original, and ornamental Design for a Tray, of which the following is a specification, reference being had to the accompanying drawings, forming part thereof, in which

Fig. 1 is a top plan view of a tray, showing my new design;

Figs. 2 and 3 are respectively side and end elevational views; and

Fig. 4 is a partial vertical sectional view thereof taken on line IV—IV of Fig. 1.

I claim:

The ornamental design for a tray, substantially as shown.

JOHN CAUFFIEL.
